UNITED STATES PATENT OFFICE.

MELVIN L. STONE, OF LAWRENCE, MASSACHUSETTS, ASSIGNOR TO DRAPER CORPORATION, OF HOPEDALE, MASSACHUSETTS, A CORPORATION OF MAINE.

WARP STOP MECHANISM FOR LOOMS.

1,388,212.

Specification of Letters Patent. Patented Aug. 23, 1921.

Application filed March 10, 1921. Serial No. 451,224.

To all whom it may concern:

Be it known that I, MELVIN L. STONE, a citizen of the United States, residing at Lawrence, in the county of Essex and State 5 of Massachusetts, have invented an Improvement in Warp Stop Mechanism for Looms, of which the following description in connection with the accompanying drawings, is a specification, like characters on the drawings representing like parts.

This invention relates to warp stop mechanism for looms, through the agency of which the loom is stopped when a warp thread breaks or becomes too slack for weaving 15 purposes.

Various forms of warp stop mechanisms have heretofore been devised for effecting stoppage of the loom when the warp thread breaks or becomes too slack, and in the present 20 practice such warp stop mechanisms are usually located near the rear portion of the loom, and not in convenient reach of weaver. Other forms of warp stop motions have been suggested wherein the 25 drop wires or other warp detecting means has been mounted upon the lay and in convenient position for manipulation by the weaver. In this latter type of warp stop mechanism, however, the parts of the warp 30 stop motion have interfered with the work of the weaver when piecing up, and the character of the warp stop mechanism has been complicated and not well suited for its purpose.

One of the important features of the present invention consists in warp stop mechanism wherein the parts are simple in construction, effective in operation, and do not necessarily interfere with the weaver when 35 piecing up.

A further feature of the invention consists in a series of drop wires which are mounted upon the lay above the reed, and which coöperate with a feeler having a detecting 40 movement in the path above the reed, and consequently out of the way, to effect loom stoppage when the detecting movement of the feeler is arrested by a drop wire which fails to be supported by a warp thread.

Where the drop wires are mounted upon 45 the lay, each drop wire has a warp engaging portion which extends between the dents

of the reed, and consequently when the shed is formed, one of the warp threads of a pair in each dent of the reed is raised and 55 then lowered during the beat-up. This alternate engagement of the pairs of warp threads with the drop wires, permits all of the drop wires to assume a lowered position when the shed is closed, and a further 60 important feature of the present invention, therefore, consists of drop wires of peculiar construction which have warp engaging portions extending between the dents of the reed and laterally projecting portions which 65 rest upon the reed cap when the drop wires are lowered as the shed is closed, or when a drop wire fails to be supported by a broken or too slack warp thread.

A further characteristic of the invention 70 consists in the series of drop wires having upwardly extending slots which are provided with wide open upper ends to permit the drop wires to be readily put in and taken out of the loom, and in view of the 75 fact that the drop wires are provided with laterally projecting portions or shoulders which rest upon the reed cap when the drop wires are not supported in raised position by warp threads, the open ended slots 80 enable the drop wires to be readily engaged with the drop wire guiding means, or disengaged therefrom.

During the weaving operation the reed is liable to longitudinal displacement at times, 85 and a further feature of the invention consists in means for adjustably securing the reed in position with the warp engaging portions of the drop wires extending between the dents of the reed.

Other features of the invention will be hereinafter described in connection with the above, and in relation to the accompanying drawings which show one good form of the present invention.

In the drawings:

Figure 1 is a sectional elevation of a loom from front to rear having the present invention applied thereto;

Fig. 2 is a perspective view on an enlarged 100 scale showing more particularly the association of the warp stop motion of the present invention with the reed;

Fig. 3 is a sectional detail showing the

means on the lay for transmitting movement of the feeler to the stop mechanism;

Fig. 4 is a detail partly in section showing the stop finger and its controlling means;

Fig. 5 is a front elevation showing more particularly the reed, the drop wires mounted above the reed cap, the feeler and the adjustable means for holding the reed in longitudinal position on the lay;

Fig. 6 is a sectional detail in perspective showing a portion of the reed cap, the guide bars for the drop wires, and the preferred form of drop wire.

15 The warp stop motion of the present invention is adapted for application to any ordinary loom without material change in the construction thereof, as will more fully appear, and as indicated in Fig. 1, the loom frame 1 may be of usual construction, as may also be the lay 2, the lay swords 3, the crank shaft 4, the arm or pitman 5 connected to the crank shaft and lay for imparting to the latter its beat-up movements.

20 25 The lay 2 has the usual reed receiving groove or socket 6 (Fig. 2), and the cap 7 is likewise provided with a groove 8. In the opposed grooves 6 and 8, the upper and lower bars of the reed are received.

30 35 The drop wires are mounted upon the lay above the reed, and in the present instance of the invention, each drop wire 9 as best shown by Figs. 2 and 6, is provided with an upwardly extending slot 10 having the upper end portion of the slot opening at 11. Each drop wire 9 is provided with a laterally projecting portion which, in the present instance of the invention, is adapted to engage the upper surface of the reed cap 7.

40 45 The lateral projection is preferably formed by a shouldered portion 12. Extending downwardly from the upper portion of the drop wire is the lower arm 13, the terminal point of which is provided with the warp engaging portion 14 which extends between the dents of the reed, as best indicated in

Fig. 2. Mounted in suitable supports 15 rising from the reed cap 7 is the drop wire guide 16 which passes through the open slots 50 55 10 of the drop wires, the supports 15, one preferably adjacent each end of the reed cap, as indicated in Fig. 5, also affording support for a brace 17 which engages the rear portion of the drop wires to prevent their displacement when a drop wire is engaged by the feeler, as will more fully appear.

The character of drop wires in the present invention is such that by reason of the open ended slots 10, the drop wires may be placed in or taken out of their operative position without disturbing other drop wires of the series, and since all of the drop wires are lowered when the shed is closed, the lateral projection or shoulder 12 with which each

drop wire is provided, may conveniently rest 65 upon the top surface of the reed cap 7, and then be raised therefrom when the shed is open and one of the warp threads of each which pass between the reed dents is raised.

The feeler has a detecting movement and 70 is arrested by a drop wire when such drop wire fails to be supported by a warp thread.

In the present instance of the invention, the feeler 18 is carried by the arms 19, one adjacent each end of the lay, and may be 75 further supported by intermediate arms 20 (Fig. 5). The arms 19 which carry the feeler 18 are loosely mounted on the rod or shaft 21 which is supported in bearings 22 on the reed cap. A spring 23 is connected at one end to the feeler carrying bar 19, as indicated in Fig. 2, and the other end of the spring is connected to a lug 24 carried by the feeler cap, the construction being such that the feeler 18 will be moved 80 clockwise under the tension of the spring 23 until a stop 25, which may be formed as a knife joint between the feeler arm 19 and bearing 22, limits the action of the spring.

Secured to the rod 21 is the feeler actuating arm 26 between which and the arm 19 (Fig. 2) is the spring 27, the construction being such that movement of the actuating arm 26 contra-clockwise, effects through the spring 27 a yielding movement of the feeler 90 95 18 to the left (Fig. 2).

The actuating arm has a down-turned end 28 adapted to be engaged by the upwardly extending arm 29 of an actuator pivoted at 30 on the lay. The other arm of the actuator 100 extends rearwardly as at 31, and rests upon a cam 32 carried by the crank shaft 4, the construction and timing of parts being such that the feeler shall have imparted to it its feeling movement to detect whether any one 105 of the drop wires is in lowered position when the shed is open as indicated in Fig. 1. The arm 31 is sufficiently long so that as the lay beats up, it will maintain its bearing upon the cam 32.

110 The feeler has connected thereto means for effecting loom stoppage when the feeler is arrested in its detecting movement. Such means is preferably formed by a flexible wire incased in a coil or armor, and as 115 illustrated in Figs. 2, 3 and 4, one of the feeler arms 19 has mounted upon it a socket member 33 (Fig. 2) into which extends the incased flexible wire 34. The wire 34 is secured in the socket 33 by the set screw 35, 120 and extends from the socket 33 through a casing 36 mounted at the rear of the reed cap 7. The wire 34 extends from the socket 36 through the armor or coil 37, and leads to controlling position with respect to the 125 stop finger 38 at the front of the loom. Inasmuch as the lay has movement toward and from the front of the loom, the incased wire

34 is slack between the lay and the stop finger 38 as indicated in Fig. 1.

The end of the incased wire 34 is received in a socket piece 39 supported at the front 5 of the loom, and the end of the wire 34 rests against the lower end of an elevator 40, upon the upper end of which rests the stop finger 38. A spring 41 normally acts upon the stop finger 38 tending to depress it, and to move 10 the end of the stop finger into a lowered position to be engaged by the operating member 42 (Fig. 2). The operating member 42 is carried by a lever 43 pivoted to the loom frame at 44, and having on its rearwardly 15 extending arm 45 a roller 46 which rests upon the double acting cam 47 mounted upon the cam shaft 48, the construction being such that the operating member 42 is given its forward movement in timed relation with 20 each beat-up movement of the lay.

The stop finger 38, as indicated in Fig. 2, is pivotally secured at 49 to a slide 50, the front end portion of which bears against the end 51 of the knock-off lever pivoted at 52 25 on the shipper stand. The end 53 of the knock-off lever rests against the front portion of the shipper 54, which, when the loom is running, is held in its operative position by the usual notch 55 in the shipper stand. 30 The construction is such that should the stop finger 38 be moved forwardly by the operating member, the knock-off lever will detach the shipper from its holding notch, and effect loom stoppage.

35 When the shed is closed during the beat-up, all of the drop wires 9, as seen in Fig. 2, rest upon the top surface of the reed cap. When the shed is open, however, the warp engaging end portions 14 of the drop wires 40 will be engaged by the warp threads *a* in the upper plane of the shed, and will lift all 45 of the drop wires into an upper position, as indicated in Fig. 1, provided all the warp threads are intact or not too slack. During such relation of parts, the stop finger 38 will be raised into its upper position (Fig. 1) by the incased wire 34 as the feeler 18 moves in its detecting action, and will consequently not be engaged by the operating 50 member 42, so that the loom will continue to run. When, however, any one of the drop wires is permitted to remain lowered by a broken or too slack warp thread, the detecting movement of the feeler 18 will be arrested by the lowered drop wire, and the stop finger 38 will remain lowered into the path of movement of the operating member 42 and knock-off loom.

Inasmuch as the ends of the drop wires 60 extend between the reed dents, and such reed is liable at times to have an endwise movement during weaving, it is desirable to lock the reed in its position with the ends of the drop wires extending between the dents. In

the present instance of the invention, the 65 front portion of the reed cap 7 has secured to it the plate 56 provided with a slot 57, and a series of corrugations or teeth 58. Adjustably connected to the plate 56 is the reed lock 59 which may be conveniently formed 70 as a finger having a portion 60 through which passes the locking bolt 61, the head of which is engaged at the inner surface of the slotted plate 56. The lower end portion of the lock 59 has a rearwardly extending end 75 62 which extends backwardly beyond the reed, and engages the end dent of the reed to hold the reed from endwise movement. One of the locking devices substantially as described will be placed at each end of the 80 reed as indicated in Fig. 5, so that all endwise movement of the reed in either direction will be obstructed, and the reed will be held in the desired adjusted position by the lock. 85

The arrangement and construction of parts is such that the drop wires are disposed above the reed and preferably above the reed cap, and while not supported by the warp threads when the shed is closed, the shoul- 90 dered portion 12 of the drop wires will be supported upon the upper surface of the reed cap. When the shed is opened, the warp threads in the upper plane of the shed, provided all warp threads are intact and in 95 working condition, will raise the drop wires from the position (Fig. 2) to that of Fig. 1, and the feeler 18 will partake of its feeling movement rearwardly, and cause the flexible wire 34, to lift the stop finger out of the path 100 of the operating member 42. Should any one of the warp threads be broken at such times, or should any warp thread become broken as the shed is formed, its associated drop wire will assume its lowered position 105 and obstruct the detecting movement of the feeler, whereupon the loom will be stopped.

By locking the reed from longitudinal dis- 110 placement on the lay, the proper association of the drop wires and warp threads is main- tained, and the reed held in adjusted position longitudinally.

What is claimed is:—

1. In a warp stop mechanism for looms, the combination of the lay, a reed mounted on the lay, a series of drop wires mounted on the lay above the cap of the reed, and each having a downwardly extended portion which projects between adjacent reed dents, a feeler mounted upon the reed cap 120 and having a detecting movement above the reed to engage a drop wire above the reed cap when the drop wire fails to be supported by a warp thread, and means for stopping the loom when the feeler is arrested by a drop wire. 125

2. In a warp stop mechanism for looms, the combination of the lay and reed, a se-

ries of drop wires mounted upon the lay and having wide portions above the reed cap, and downwardly extended portions which project between the dents of the reed, a 5
feeler having a detecting movement to engage a widened portion of a drop wire when it fails to be supported by the sharp threads, and means for effecting loom stoppage when the detecting movement of the feeler is arrested.

3. In a warp stop mechanism for looms, the combination of the lay and reed, a series of drop wires mounted upon the lay and having shoulder portions for arresting 15
the downward movement of a drop wire by engagement with the cap of the reed when the drop wire fails to be supported by a warp thread, a feeler having a detecting movement and adapted to be arrested by a drop wire when it is in dropped position, and means for stopping the loom when the feeler movement is arrested.

4. In a warp stop mechanism for looms, the combination of the lay and reed, a series of drop wires mounted upon the lay and having shoulder portions for arresting the downward movement of a drop wire by engagement with the cap of the reed when the drop wire fails to be supported by a warp 25
thread, a warp thread engaging portion extending downwardly from each drop wire back of the lay and projecting between dents of the reed, a feeler having a detecting movement and adapted to be arrested by a drop wire when it is in dropped position, and means for stopping the loom when the feeler movement is arrested.

5. In a warp stop mechanism for looms, the combination of a series of drop wires 40
having widened upper portions provided with upwardly extending slots which are open at the top, a laterally projecting portion extended from each drop wire, and a rest adapted to be engaged by the projecting portion of a drop wire to determine the position of a drop wire when it fails to be supported by a warp thread.

6. In a warp stop mechanism for looms, the combination of a series of drop wires 50
having widened upper portions provided with upwardly extending slots which are open at the top, a laterally projecting portion extended from each drop wire, a rest adapted to be engaged by the projecting portion of a drop wire to determine the position of a drop wire when it fails to be supported by a warp thread, and a drop wire guide extending through the slots of the drop wires below the open upper ends.

60 7. In a warp stop motion for looms, the combination of the lay and reed, a drop wire guide carried by the lay above the reed, a series of drop wires having their upper portions provided with upwardly extended slots

which are open at the top and lateral projecting portions adapted to engage the reed cap when the drop wires fail to be supported in raised position by the warp threads.

8. In a warp stop motion for looms, the combination of the lay and reed, a drop wire guide carried by the lay above the reed, a series of drop wires having their upper portions provided with upwardly extended slots which are open at the top, lateral projecting 70
portions adapted to engage the reed cap when the drop wires fail to be supported in raised position by the warp threads, a feeler having a detecting movement in a path 75
above the reed cap, and means for stopping the loom when the feeler is arrested by a drop wire.

9. In a warp stop motion for looms, the combination of the lay, and reed, a series of drop wires each having a warp thread 80
engaging portion extending between the dents 85
of the reed, guiding means for the drop wires mounted upon the lay above the reed, a feeler mounted upon the lay above the reed and having a detecting movement, and means for stopping the loom when the feeler 90
engages a drop wire above the reed and has its detecting movement arrested.

10. In a warp stop motion for looms, the combination of the lay and reed mounted 95
thereon, drop wire guiding means mounted on the lay above the reed, a series of drop wires having guiding portions which extend above the reed to engage the drop wire guiding means and also having warp thread 100
engaging portions which extend between the dents of the reed, a feeler having a detecting movement above the reed and adapted to be arrested by engagement with a drop wire above the reed when the wire fails to be supported by a warp thread, and means for stopping the loom when the feeler is arrested.

11. In a warp stop motion for looms, the combination of the lay and reed, a series of drop wires mounted on the lay above the reed and having warp engaging portions extending between the dents of the reed and lateral projecting portions which engage and rest upon the reed cap when the detectors 110
are not supported in raised position by the warp threads.

12. In a warp stop mechanism for looms, the combination of a series of drop wires 115
adapted to be supported by the warp threads 120
and each having its upper portion provided with an upwardly extended slot which is open at the top of the drop wire, a drop wire guide which extends through the open slots of the drop wires, and a stop for stopping 125
the downward movement of a drop wire before the open slot becomes disengaged from the guide.

13. In a warp stop motion for looms, the combination of a series of drop wires adapted to be supported in raised position by warp threads and each having its upper portion provided with an upwardly extending slot which is normally open at the top, a drop wire guide on which the drop wires may be placed by upward movement of the drop wires, a stop for stop-

ping the downward movement of a drop wire when it is released by a warp thread and before the open ended slot becomes disengaged from the guide bar, and means for stopping the loom when a drop wire fails to be supported by a warp thread. 10 15

In testimony whereof, I have signed my name to this specification.

MELVIN L. STONE.
